CLAIM

The ornamental design for a focus control device, as shown and described.

DESCRIPTION

FIG. 1 is a top and left side perspective view of a focus control device, showing my new design;
FIG. 2 is a bottom and right side perspective view thereof;
FIG. 3 is a front view thereof;
FIG. 4 is a rear view thereof;
FIG. 5 is a top plan view thereof;
FIG. 6 is a bottom plan view thereof;
FIG. 7 is a right side view thereof; and,
FIG. 8 is a left side view thereof.

The broken lines illustrate portions of the focus control device and form no part of the claimed design.
